BUTTON

John M. Clark, Detroit, Mich., assignor to
 Universal Button Fastening & Button Company, Detroit, Mich., a corporation of Michigan

Application April 2, 1932, Serial No. 602,702

2 Claims. (Cl. 24—90)

This invention relates to buttons and among other objects aims to provide a durable decorative metal button at low cost.

The nature of the invention may be readily understood by reference to one illustrative button embodying the invention and illustrated in the accompanying drawing:

In said drawing:

Fig. 1 is a transverse section through the button;

Fig. 2 is a plan view of the top of the button; and

Fig. 3 is a sectional elevation of the button head covering shell before the latter has been affixed to the button.

Buttons of the type to which this invention relates are largely employed on overalls and workmen's clothing. They should be durable to prevent damage in the laundry process, and they should be rust proof to avoid rust stains on the garment. Preferably, the button should have a decorative top and be capable of displaying a trade-mark or trade name in embossed or other decoratively displayed characters. While buttons made from brass or the like answer these qualifications, their cost under competitive conditions is prohibitive. Sheet metal buttons made of rust proof or other sheet metal have been largely used for the foregoing purposes; but besides having a high manufacturing cost, they retain laundry fluids on their hollow interior which later escapes on or stain the garment.

The illustrative button is particularly adapted for the foregoing and other purposes, since it may be produced at low cost, is rust proof and has an attractively decorative or embossed head. It comprises a solid soft steel body 10 consisting of an integral head 11 and shank 12. The button may advantageously be made from short sections of rod or heavy wire stock of a diameter (slightly less than one-fourth inch in this instance) substantially that of the shank 12 of the button. In forming the button the cylindrical wire blanks of the proper length are subjected at one end to head forming operations which gradually flatten one end of the blank into a button head. The other end of the blank is held against substantial lateral expansion and thus provides the shank of the button. The diameter of the button head is largely governed by the selected initial length of the blank. Because of the inherent strength and rigidity of the solid soft steel shank of the button, the shank may be made of a smaller diameter than is practicable where the button is made from sheet metal. The small diameter

shank avoids undue wrinkling or buckling of the cloth at the button hole.

During the formation of the button the end of the shank is formed with a curved die cup or recess 13 which serves to upset or bend a pronged attaching fastener. In case of attachment by a double pronged fastener, the prongs are bent or upset by the curved surface 14 of the die cup around a bar 15 or its equivalent extending transversely across the die cup. Single pronged fasteners are upset directly or indirectly by the curved die surface so that the prong cannot be withdrawn through the small opening into the die cup through which the fastener prong enters. The fasteners are generally made of steel so as to penetrate without bending, any desired number of thicknesses of hard, close textured cloth, and therefore require an equally hard or harder die surface to upset them. Aside from the advantage of low cost and strength, by making the button from a solid steel blank, an adequately hard die surface 14 is provided by the die cup formed in the steel blank itself and without the addition of other elements which would be necessary to assist in upsetting a fastener prong if the button were formed of softer or more expensive metal. Indeed, in the formation of the die cup the surface of the metal is compacted and made very dense and substantially increased in hardness.

The steel button body is made rust proof in this instance by cadmium plating. This plating while admirable for protection does not possess the requisite characteristics itself to serve as a superficial decorative covering for the button head. In the present case, the head of the button is covered by a specially prepared dyed thin aluminum shell 16. The aluminum is colored while in sheet form, thereby avoiding any treatment of the shells after they have been formed.

The sheet aluminum is colored in the present instance by applying aniline dye (generally to both faces of the sheet) and permitting it to penetrate the porous surface of the sheet. The aluminum which is naturally porous to some extent is rendered more porous by treating it (before the application of the dye) in an electrolytic bath with the aluminum sheet serving as the anode, the arrangement of electrodes being the reverse of that in electroplating. The flow of electric current instead of plating the sheet leaves the surface in a substantially porous condition, the pores being of course microscopic in size and invisible to the eye. The surface of the sheet therefore is of a character to permit substantial pene-

tration by the dye so that it cannot be rubbed off either in the shell forming operations or in normal use of the button. Indeed, the dye or coloring is practically an integral part of the metal surface 5 of the sheet and does not crack even when the metal is sharply bent. Intricate designs may be embossed in the shells without visibly disturbing the color.

The color is additionally protected against the 10 action of strong washing fluids by applying a fluid lacquer to the sheet which penetrates the surface by entering the pores in the sheet and does not therefore exist merely as a superficial coating. Even though the surface lacquer is 15 later worn off, the lacquer in the pores of the metal protects the color against deleterious effect of strong washing and other fluids.

Because of the minute character of the pores 20 in the sheet, the colored sheet assumes a highly polished effect which remains even through forming and embossing operations in which the metal may be sharply bent.

After formation of the shell which is provided 25 with a crimping margin 17, it is applied to the head of the button and the margin 17 crimped under the button head. As here shown (Fig. 1), the button head is marginally rabbeted at 18 to receive the crimping margin whose outer face thus lies flush with the under-surface of the button head.

A two tone effect may be produced on the shell 30 by tumbling the finished button with a small quantity of mild abrasive such as powdered pumice stone. This wears down the color on the high points of the embossing 19 on the shell either 35 exposing the aluminum or changing the tone of the color. The cost of this operation is negligible as compared to the cost of producing two tone effects by means of enamel on embossed shells.

The inventive button compares favorably in 40 cost (but is otherwise superior) with that of solid buttons having merely a decorative plating. In the latter case, the application of the decorative plating affects the efficiency of the rust proof 45 cadmium plating, and therefore impairs the rust resisting qualities of such a button, particularly since the action on the cadmium plating is not confined alone to the button head but extends over the entire surface of the button. In the present button, on the other hand, the cadmium plating 50 of the steel body of the button remains with full efficiency, and the decorative rust proof shell is not only less expensive than other rust proof

decorated shells but it surpasses any other shell in decorative qualities. Buttons may be produced with varying colors without changing the manufacturing process in any respect except to use aluminum sheet of the proper color. It is also possible by this method to secure a range of colors much greater than with enamel shells and at no increase in cost particularly as compared with the increase in cost in applying different special enamel colors to small batches of buttons.

Because of the wide color range of aniline dyes 10 it is possible to provide button shells of a color to match a particular color of cloth. This is particularly desirable for children's clothing where the matter of color harmony is important.

In sew-on buttons for children's clothing, work shirts and the like, it is not necessary to embody a fastener upsetting die in the button. The inventive sew-on buttons may be made by stamping the button from the aforesaid dyed 20 aluminum sheets of the desired color, and perforating the button blank to provide thread holes. Such buttons may or may not be embossed, and if embossed may be given a two-tone effect by tumbling as aforesaid.

Obviously the invention is not limited to the details of the illustrative button or the methods of manufacturing it since these may be variously modified. Moreover it is not indispensable that all of the features be used conjointly, since 30 various features may be used to advantage in different combinations and subcombinations.

Having described my invention, I claim:

1. A button of the character described comprising in combination a steel button body consisting 35 of a head and shank and having a cadmium plating thereon, and a thin aluminum shell covering the head of the button, said shell being superficially porous and being penetrated by a coloring dye and having applied thereto a protecting lacquer, said colored shell being formed with a decorative embossing on its top.

2. A button of the character described comprising in combination a steel button body consisting 45 of a head and shank, and a thin aluminum shell covering the head of the button, said shell being superficially penetrable and being penetrated by a coloring dye and having applied thereto a protecting lacquer, said colored shell being formed with a decorative embossing on its 50 top.

JOHN M. CLARK.
